UNITED STATES PATENT OFFICE.

EDWIN J. BLOOD, OF CHICAGO, ILLINOIS.

CANNON.

Application filed September 9, 1926. Serial No. 134,558.

This invention relates, generally, to cannons or heavy ordnance, but has particular relation to that type of cannons disclosed and claimed in Patent No. 985,220 issued 5 to me on the 17th day of May 1910.

Like the invention of the aforesaid Letters Patent, the present invention has for its principal object to provide means whereby the largest type of guns or cannons of 10 great strength and durability can be constructed without the use of heavy forgings, but instead thereof, by the employment of a large number of small parts reduced to very thin or sheet like formation by a rolling process or otherwise, thereby attaining 15 superior and known quality of the parts and avoiding the risk of hidden and inherent defects and integral strains attendant upon heavy forgings.

Another object of the present invention 20 is, to render this manner of constructing the larger type of cannon more perfect, by providing new structural features which will function easily and furnish practical means 25 for disconnecting the parts of the gun or for knocking the same down.

In affording means to accomplish this result, it is evident that the value and importance of a structure embodying such a 30 construction is very important and increases the value of the invention.

Another object of the invention is, to 35 provide means in the construction of the cannon for equally distributing the initial strain or tension thereof and for maintaining it at high pressure at the time it is subjected to the shock of explosion.

A further object of the invention is, to 40 provide improved means for attaining even or uniform pressure or tension of the inner and outer barrel or barrels, when the former is inserted in the bore of the latter, by employing longitudinally slotted sleeves of ductile material which is inserted between 45 the barrels.

Still another object is to provide such sleeves with longitudinal slots in order that 50 they may be more readily placed in position, and also for the purpose of preventing "buckling" or crinkling of the same when so positioned.

Other objects and advantages of the invention will be disclosed in the following description and explanation, which will be 55 more readily understood when read in conjunction with the accompanying drawings,

which illustrate an embodiment of the present invention, it being understood that modifications and changes may be resorted to without departing from the spirit of the invention so long as they fall within the scope 60 of the appended claims.

In the accompanying drawings:

Fig. 1 is a plan view of a cannon constructed according to my present invention. 65

Fig. 2 is a plan longitudinal sectional view taken on the horizontal medial line of Fig. 1, showing the manner of securing the spools which carry metal reenforcing disks or members, together, but with the barrels omitted. 70

Fig. 3 is an enlarged horizontal sectional view of a portion of the cannon showing a plurality of barrels having mounted thereon a spool loaded with or surrounded by a number of reenforcing and apertured disks for 75 withstanding cross-sectional strain and also illustrating the ductile tubes interposed between the barrels of the cannon and one between the outer barrel and said spool.

Fig. 4 is a side view in elevation of a part 80 of the cannon illustrating the manner of connecting the aforesaid spools together longitudinally.

Fig. 5 is an underneath plan view of a 85 portion of the body of the cannon, and one of the strengthening or fastening girders in position thereon.

Fig. 6 is a longitudinal sectional view of a gun barrel made up of a plurality of barrels and ductile tubes interposed between 90 each.

Fig. 7 is a detached perspective view of a portion of one of the ductile tubes or pieces.

Fig. 8 is a horizontal sectional view of the breech end of a cannon constructed according to the invention showing it equipped 95 with a breech-block and firing mechanism.

Fig. 9 is a vertical sectional view taken on line 9—9 of Fig. 8 looking in the direction indicated by the arrows and 100

Fig. 10 is a fragmental sectional view taken on line 10—10 of Fig. 8 looking in the direction indicated by the arrows showing another manner of connecting the flanges of the spools together by means of a girder 105 or strengthening member.

Corresponding characters of reference, 110 designate like parts throughout the different views of the drawings.

The crystalline formation of a massive steel ingot weighing many tons is but partially changed to a fibrous formation by the

process of forging, but when reduced by rollers or otherwise to very thin or sheet like form, the metal is changed entirely to a fibrous formation increasing its tensile strength several hundred per cent, sometimes reaching as high as three hundred thousand pounds per square inch while ninety thousand pounds per square inch is high in a massive forging, hence to insure the greatest strength and durability in the larger type of guns or cannons I prefer and usually will employ metal of a fibrous formation and in pieces of such size and form as may be desired to attain high tensile strength and to enable parts of superior and known quality only to be selected and incorporated in the structure of the cannon.

It will therefore be understood that it is the purpose of the present invention to employ relatively small parts rolled or otherwise formed very thin, or sheet like parts, in the construction of a cannon, in order to obtain the greatest strength and to know that the parts comprising the cannon are without flaws, imperfections or weakness.

This has been obtained by the structure constructed according to the invention set forth in my aforesaid patent. However, said patent sets forth a structure that is deficient in some respects and it is the purpose of the present invention to correct said deficiencies, as well as, to provide means for more perfect, easy and uniform pressure or tension of the inner and outer barrels, and furthermore, to render it more easy to assemble the parts and detach them, than has heretofore been done.

As my present invention is similar in every respect to the structure set forth and claimed in the aforesaid patent, with the exception of the means hereinafter described of firmly attaching for easy detachment the strengthening members or girders to the flanges of the spools which carry the disk like reenforcing members, and with the exception of providing easy means for detaching said girders from the spools, and with the exception of rendering it an easy matter to place the ductile members between the barrels and spools when desired and in such a manner as to beneficially effect the efficiency of said ductile members in a greater degree than before, and with the exception of the firing mechanism, I will describe the gun in a general way, only, but will set forth fully hereinafter the structure or combined parts which I claim as new and will specify in the annexed claims.

Referring now to the drawings it will be seen and understood by reference to Figs. 1 to 4 inclusive that the cannon comprises an inner barrel 15 an outer barrel 16 and in some instances other barrels 17 interposed between the inner and outer barrels, all of which barrels are tapered from the breech

towards the muzzle end of the cannon as in the said patented construction. Surrounding the outer barrel are a number of longitudinally extended spools, each made up of an oppositely tapered body portion 19 each body portion having at opposite ends an annular flange 20 extended outwardly around the outer barrel, or as shown in Fig. 3 around a slotted sleeve or tube 21 of copper or other ductile material such as white lead, one of which sleeves is interposed between the adjacent surfaces of the barrels as shown in Fig. 3 of the drawings. The body portion 19 of each of the sections composing each spool is surrounded by thin steel or metal disks 22 and held in close relation as shown by the flange 20 of the inner section of each spool. These sections are fitted on the outer barrel so that the flanges 20 will closely contact with each other. Near the muzzle end of the cannon and surrounding the barrels thereof is a collar 23 having oppositely disposed transverse openings located at the sides of the barrels.

The spools, or rather the flanges 20 thereof abutting each other are held in firm position by means of girders or strengthening members 24 which extend the length of the cannon and have their ends adjacent its muzzle reduced and screw-threaded to receive the nuts 25 so as to tighten the collar 23 against the disks 22 on the spool adjacent said collar and also for holding said members in edgewise engagement with the flanges of the spools. For this engagement each of the girders 24 is provided at proper spaced points to stride said flanges with recesses 26 which are somewhat larger than the thickness of the flanges as will be understood by reference to Figs. 2, 4 and 10 of the drawings. By this arrangement it is obvious that the recesses so formed provide open spaces between their edges on each side of the flanges and said flanges. Into each of these recesses is located an angular or L-shaped wedge 27 the head 28 or outer portion of each of which is provided with an opening through which is extended a screw bolt 29 which also extends in the construction shown in Figs. 1 and 4 through openings in the girders 24 at the longitudinal sides of said recesses. Located on the lower surface of each of the girders 24 is a keeper or member 30 having at each of its ends an in-turned flange which rests longitudinally against the girder on each side of each of said recesses. Each keeper or member 30 is provided with openings through which the screw bolts 29 are extended and secured in place by means of nuts 31 applied thereto. Thus it will be understood the arrangement for fastening the girders in place will be very efficient, easily applied and readily detached and at the same time enabling the girders to be removed when desired from the

said flanges or placed thereon in any easy manner, which operation cannot be performed by the structure of the aforesaid patent.

5 Instead of using the structure shown in Fig. 4 and above described for engaging the girders 24 with the spool flanges 20 I may use tap screws 29^a see Fig. 10 which are extended through the openings in the 10 heads 28 and each tapped into an opening 32 of the girder on the longitudinal side of each of said recesses. In either of these arrangements it is manifest that means for securely clamping the girders to the spool 15 flanges is afforded, which means can be almost instantly removed so as to permit the girders to be easily removed.

In order to attain even or uniform pressure or tension of the inner and outer barrels 20 or of a plurality of barrels, I employ a very thin sleeve 21 of ductile material which is provided with an open ended slot 21^a and placing it on one of the barrels by nesting them together so that the outer surface of 25 each barrel will have the ductile sleeve interposed between it and the adjacent inner surface of another barrel as is clearly shown in Figs. 3 and 6 of the drawings. By this arrangement it will be understood that by 30 slotting the sleeves as shown, they can be more easily and accurately fitted on their respective barrels without any danger of crinkling and that thus the pressure transmitted to all of the barrels will be even and 35 uniform.

In Fig. 3 I have shown a ductile sleeve 21 interposed between the outer barrel and the body portion of the spools which construction I may sometimes employ.

40 In Fig. 6 is illustrated a gun made of three barrels, that is, an inner barrel 15 an outer barrel 16 and an intermediate barrel 17 and having omitted from said group of barrels the spools and their reinforcing disks, 45 as well as, the means for securing said spools in position. A gun barrel made according to this last named construction which it will be understood is provided with ductile sleeves 21 of the construction shown in 50 Fig. 7 will be highly adaptable for use on air-planes and for the lighter type of ordnance.

55 Referring now to Figs. 8 and 9 of the drawings it will be seen that the breech-block 35 which may be of any preferred or the usual kind is provided near its outer end with an annular groove 36 into which is fitted the forward end of a frame 37 which extends rearwardly from said block 60 and constitutes a part of my improved firing mechanism. This frame 37 has its upper and lower portions transversely united by a bolt 38 which extends diametrically through the head of the breech-block and serves to 65 hold the forward ends of the frame 37 se-

curely in the channel or groove 36. The head of the breech-block has centrally therein an opening through which a firing rod 39 movably extends into or at the rear end of the inner barrel 15 and through the rear 70 end of the frame 37. This member is provided with a fixed transverse projection 40 within the frame 37 against one end of which a spring 41 rests, the other end of which spring contacts with a cross member 75 42 of the frame which member is also apertured for said firing rod which has at its rear end a hand piece 43 for retracting said rod to its cocked position as shown within the frame 37 a rod 39 is provided with a notch 80 44 for the reception of a trigger 45 which is transversely mounted in the rear of the frame 37 and is actuated towards the rod by means of a spring 46 which rests at one of its ends against the flange 37 and at its 85 other end against a releasing frame 47 through which the trigger 45 extends in any suitable fixed relation. This frame 47 is provided in its rear and front wall with elongated openings 48 through which the 90 firing rod extends. From the lower portion of the frame 47 depends a connection 49 through the frame 37 which connection has near its lower end a laterally extending pin 50 for engagement with the forked end of the shorter arm 51 of a bell-crank-lever 52 to the longer arm of which is secured one end of a cord or cable 53 which may lead to any distance from the cannon and is employed for moving the longer arm or said 100 bell-crank-lever in the proper direction to release the trigger 45 so as to allow the spring 41 to force the firing rod 29 forwardly to explode the charge.

It will be understood that any or all of 105 the barrels used in the construction of the cannon, except the rifled barrel may be tapered on both their surfaces on either their inner or outer surfaces.

Having thus fully described the invention, what I claim as new and desire to secure by Letters Patent is:—

1. In a cannon of the class described, the combination of a barrel, a series of spools mounted thereon, each spool having tubular body portions fitted one within another and having at opposite ends an outwardly extended flange, reinforcing material surrounding the outer body member, and means to secure said spools together under tension 115 on the barrel, said securing means consisting of a plurality of girders or strengthening members each having spaced recesses on its edge adjacent said spool flanges to embrace a pair of the same and being somewhat larger than the united thickness of each member of each pair of flanges, means inserted in each of said recesses on each side of the flanges for holding the latter under 120 high pressure and means to detachably con- 130

nect said inserted means to the girders or strengthening members.

2. A cannon of the class described comprising a barrel tapered towards its muzzle end, a plurality of spools mounted longitudinally thereon, each spool having tubular body portions fitted one within another and having at opposite ends an outwardly extended flange, the inner body portion of the spools being tapered on its inner surface to correspond with the taper of the barrel, a plurality of comparatively thin girders or strengthening members mounted on said flanges and each having spaced recesses on its edge adjacent said spool flanges to embrace a pair of the same and being somewhat larger than the united thickness of each member of each pair of flanges, a wedge shaped member inserted in each of said recesses on each side of the flanges for holding the same under high tension or pressure and means detachably connecting said wedge shaped members to the girders or strengthening members.

23 3. A cannon of the class described com-

prising a rifled inner barrel having its outer surface inclined towards its muzzle end, a longitudinally split sleeve of ductile material tapered towards its muzzle end and fitted on the outer surface of the inner barrel and an outer barrel fitted on the outer surface of said sleeve.

4. A cannon of the class described comprising an outer and an inner barrel fitted one in the other, a longitudinally split ductile sleeve between said barrels the said outer barrel being tapered towards its muzzle end and spools carrying reinforcing members and having their inner surfaces tapered to correspond with the taper of said outer barrel mounted in contacting relation with one another on the last named barrel.

5. A cannon of the class described comprising a plurality of spools each spool having tubular body portions fitted one within another and having at opposite ends an outwardly extended flange, and ductile material such as white lead on the outer surface of the inner body portion of each spool.

EDWIN J. BLOOD.
